(57) **CLAIM**

We claim the ornamental design for a battery, as shown and described.

DESCRIPTION

FIG. 1 is a perspective view of a battery according to an embodiment.

FIG. 2 is a bottom side view of the battery of FIG. 1.

FIG. 3 is a top side view of the battery of FIG. 1.

FIG. 4 is a right side view of the battery of FIG. 1.

FIG. 5 is a left side view of the battery of FIG. 1.

FIG. 6 is a back end view of the battery of FIG. 1.

FIG. 7 is a front end view of the battery of FIG. 1.

FIG. 8 is a perspective view of a battery according to another embodiment.

FIG. 9 is a bottom side view of the battery of FIG. 8.

FIG. 10 is a top side view of the battery of FIG. 8.

FIG. 11 is a right side view of the battery of FIG. 8.

FIG. 12 is a left side view of the battery of FIG. 8.

FIG. 13 is a back end view of the battery of FIG. 8; and, FIG. 14 is a front end view of the battery of FIG. 8.

The elements shown in broken lines form no part of the claimed design and are included for the purpose of showing the environment of the claimed design. Any broken lines having unequal line segments indicate the boundary of the claimed design.
